UNITED STATES PATENT OFFICE.

JAMES DAVID MURPHY, OF MONTREAL, QUEBEC, CANADA.

ESCAPEMENT MECHANISM IN TYPEWRITING MACHINES.

Application filed July 25, 1925. Serial No. 46,067.

The invention relates to escapement mechanism in typewriting machines, as described in the present specification and illustrated in the accompanying drawings that form 5 part of the same.

The invention consists essentially of the novel features of construction pointed out broadly and specifically in the claims for 10 novelty following a description containing 10 an explanation in detail of an acceptable form of the invention.

The objects of the invention are to facilitate the operations in typewriting whereby 15 the speed of the operation is accelerated; to limit the periods of spacing by the speed of 20 the spacing dog; to reduce the noise due to this particular part and insure evenness in the movements between letters; to avoid the interference of type bars through the rapid motion in typing; to accomplish these purposes at a low cost, so as to maintain the price of machines at a low figure; and generally to provide efficiency, reliability and speed in typewriting machines.

25 In the drawings,

Figure 1 is a front elevation of the escapement mechanism of a typewriting machine.

Figure 2 is a rear elevation of the same.

30 Figure 3 is an enlarged detail of the moving panel showing the invention.

Figure 4 is a detail showing the relative positions of the moving and stationary dogs at the end of a spacing stroke.

Figure 5 is a detail showing the relative 35 positions of the dogs at the beginning of a stroke.

Figure 6 is an end elevation corresponding to the positions shown in Figure 4.

Figure 7 is an end elevation corresponding 40 to the positions shown in Figure 5.

Like numerals of reference indicate corresponding parts in the various figures.

Referring to the drawings, the dog rocker 17 is pivoted in the stationary bracket 21 45 adapted to be secured to the frame of the typewriting machine not shown.

The spacing wheel 20 is rotatably mounted on the stationary bracket 21 and is formed with the spaced teeth 22 and carries the pawl 50 and ratchet mechanism 23, which is all ordinary construction in the art, including typewriting machines.

The rack 24 engages the ratchet 23 and the 55 spring 27 pulls on the carriage 28 to which the rack 24 is secured, consequently when the carriage 28 is released by the lifting of

a key following the printing of a letter, the rack 24 turns the ratchet 23 and through the pawl 29 the spacing wheel 20 is rotated.

The rocking dog rocker 17 carries the 60 pawl 26 stationary with the bracket 17 and the moving pawl 10 journalled on the pivot 30 at its pivot bearing 12, said pivot being secured in the dog rocker 17 below the pawl 16 and slightly in advance of said pawl.

65 The moving pawl 10 is preferably formed with the neck 14 swelling into the body 31 the latter having the curved back 32 and substantially straight face 11 from which the eye lug 13 projects near to the outer end 70 of the dog.

The spring 16 follows the shape of the back 32 and is secured to the back of the neck 14 and is sprung out slightly from the back 32 and the spring 15 is secured to the 75 front of the neck 14 and is sprung out from the face 11, and this pawl 10 having the stops 18 and 19, said stop 18 being in the form of a screw head having a cam face 33. One stop 19 is a pin projecting from the stationary pawl 26 and the other stop 18 is at 80 the end of the bar which is secured to the rigid bracket 21.

In the operation of this machine the spring 85 pull on the carriage operates the escapement wheel through the pawl and ratchet mechanism and the rack 24, which is common to many machines on the market, and this operation follows the printing of a character. The downward pressure on the key rocks the 90 dog rocker 17 and this releases the moving pawl 10 from engagement with one of the teeth 22, and this moving pawl 22 is immediately released thereby and its place taken by the stationary pawl 26.

95 The return of the type bar rocks the dog rocker to its original position, meanwhile the spacing has been done. In the next spacing of the machine the moving pawl 10 is carried by a tooth 22 of the spacing wheel 100 against the pull of the spring 25 secured to the stationary bracket 21 at 34 and attached to the moving pawl 10. This movement sends the moving pawl up against the stop 19 and the spring 16 on the back of the pawl 105 hits the said stop 19 having both a cushioning and resilient or rebound action.

The lifting of the key again releases the dog 10 so that it is free to return by its own spring pull to the stop 18 where the cam face 110 slides it into place between two of the teeth 22 and also where the spring 15 hits the stop

18 having exactly the same action of cushioning and re-acting as the spring on the back of the pawl.

The constant movement of the dog 10 materially reduces the work of operation, and especially in quick typewriting material- 5 ly facilitates the increased speed. It can hardly be said that it increases the speed so much as facilitating the work of the opera- 10 tor in rapidly playing on the keys, in other words, the spacing mechanism is accelerated though the actual speed in operating the keys must naturally come from the operator.

What I claim is:—

- 15 1. In escapement mechanism in typewrit- ing machines, a toothed spacing wheel, an oscillatory member, a dog pivotally mounted on said oscillatory member and brought into action by the movement thereof, cushioning 20 and rebounding means secured to said dog, a stop on said oscillatory member and a stop apart therefrom, said stops being adapted to limit the strokes of said dog and meet said cushioning and rebounding means.
- 25 2. In escapement mechanism in typewrit- ing machines, a toothed spacing wheel oper- atively connected with a spring pulled car- riage, a reciprocating dog having a trans- 30 verse swinging movement and engaging said wheel alternately, a stationary stop, a stop moving transversely with said reciprocating dog springs secured to the front and back 35 of the dog and adapted to operate recipro- cally between said stops and a tilting member having a dog engaging said wheel intermit- tently and carrying the aforesaid dog.
- 35 3. In escapement mechanism in typewrit- ing machines, a toothed spacing wheel, a re- 40 ciprocating dog, a rocking member having a pivot bearing for said dog, stops limiting the strokes of said dog, and rebounding means secured to said reciprocating dog and contacting at the end of each stroke with said stops respectively.
- 45 4. In escapement mechanism in typewrit- ing machines, a star wheel, a dog pivotally 50 mounted and oscillating transversely to the wheel in relation to its stroke, a stationary stop having a cam face, a stop moving trans- versely with said dog, and springs forming

rebounding and cushioning members for said dog and adapted to contact with said stationary stop and said movable stop respectively during the stepping movement of the dog.

55

5. In escapement mechanism in typewrit- ing machines, a rigid bracket having a rigid stop and pivoting a rocking bracket carry- 60 ing a stop, a reciprocating dog provided with springs at its sides forming faces and adapted to engage with said rigid bracket stop and said rocking bracket stop and forming a cushioning member against the afore- mentioned stops, said rocking bracket carry- 65 ing a pivot bearing for said reciprocating dog.

6. In typewriting machines, a reciprocat- ing escapement dog having a rounded back and strip springs secured to and extending along the front and the back in relation to 70 the direction of stepping movements, a tilt- ing member carrying said dog swinging transversely in relation to the movement of said dog, a toothed escapement wheel oper- ated by said dog, and spaced stops engaged 75 respectively by said reciprocating dog in its forward and return strokes and rebounding therebetween by reason of said springs, one of said stops being rigid with said tilting member and the other being stationary and 80 having a cam face adapted to swing said tilting member.

7. In typewriting machines, an escape- 85 ment mechanism having a toothed wheel and comprising a reciprocating dog having a stepping movement between stops facilitated by springs forming a part of the dog on the sides contacting with said stops and effecting rebounding movements, an oscilla- 90 tory member carrying one of said stops and a pivot bearing for said reciprocating dog, a bar carrying the other and stationary stop, and a stationary dog from said oscillatory member and moving therewith to engage said toothed wheel to allow movement of the 95 reciprocating dog.

Signed at Montreal, Canada, this 11th day of July, 1925.

JAMES DAVID MURPHY.
